C. M. TIMPSON

COT AND BED

Filed April 5, 1923

UNITED STATES PATENT OFFICE.

CAROLINE M. TIMPSON, OF NEW YORK, N. Y.

COT AND BED.

Application filed April 5, 1923. Serial No. 629,967.

To all whom it may concern:

Be it known that I, CAROLINE M. TIMPSON, a citizen of the United States, residing at New York city, in the county of New York and State of New York, have invented certain new and useful Improvements in Cots and Beds, of which the following is a specification.

This invention relates to cots or beds and more particularly to an improved shelf attachment adapted to be used in connection with various types of cots or beds, an object of the invention being to provide an improved flexible shelf attachment which will be relatively simple and cheap in construction, light in weight, easily assembled in position or removed, adapted to be readily rolled up in compact form when not in use or for the purposes of shipment, and readily and conveniently accessible at all times attached to the bed.

A further object of this invention is to provide an improved shelf attachment for cots or beds comprising a fabric shelf suspended from a pair of supports connected to opposite ends of the bed.

A further object of this invention is to provide a suspension fabric shelf for a cot or bed, the shelf having supports adapted to be connected to the ends of the bed, and one of the supports being adjustable so as to permit the fabric shelf to be tightened or loosened.

Other objects of this invention will appear in the following description thereof, reference being had to the accompanying drawings forming a part of this specification wherein like reference characters indicate corresponding parts in the several views and wherein Fig. 1 is a perspective view illustrating my improved suspension shelf as applied to a cot or bed; Fig. 2 is an end view thereof, Fig. 3 is a fragmentary view illustrating the manner in which the fabric shelf may be adjustably supported at either end, and Fig. 4 is a detail section illustrating a form of shelf support.

Before explaining in detail the present improvement and mode of operation thereof, I desire to have it understood that the invention is not limited to the details of construction and arrangement of parts which are illustrated in the accompanying drawings, since the invention is capable of other embodiments, and that the phraseology

which I employ is for the purpose of description and not of limitation.

Referring to the drawings wherein I have illustrated a present preferred form of my invention, the same is illustrated in connection with a suitable cot or bed of any preferred form or construction. By way of example, the cot or bed comprises a suitable frame work formed from lengthwise extending side bars 9 and 10 connected together by means of transverse end bars 11 and 12. This bed frame is preferably constructed from angle iron bars, and stretched between the ends of the frame is a suitable spring mattress fabric 13. The spring mattress bed bottom is supported by the usual supporting legs 14 located at the corners of the frame.

The present improvement comprises in general, a fabric shelf located beneath the spring mattress fabric 17 of the bed and suspended between a pair of supports which are preferably detachably connected to opposite ends of the bed. The suspension shelf attachment is so constructed as to be readily assembled or connected to the bed and readily detached therefrom, and furthermore is so constructed that the entire attachment may be rolled or packed up into a very small and compact space so as to render it highly satisfactory and convenient, not only for shipping purposes, but for display purposes in stores, and for storage.

The suspension shelf proper comprises a portion of fabric 15 which may be of any suitable material such as canvas, and which is cut to the desired length and width. The fabric shelf 15 is suspended between a pair of transverse roller supports 16.

Each roller 16 is supported beneath an end of the bed by means of a pair of hook shaped supporting members 17. The several members 17 are of substantially the same construction and each comprises a flat strap or bar bent to provide a right angle portion 18 terminating in an inwardly bent hooked end 19.

It will be noted that the hooked end 19 extends with relation to the bent portion 18 at an angle less than a right angle, so that when the bar 17 is hooked over a transverse angle bar 12 of the bed frame the downwardly and inwardly bent portion 19 will effectually prevent any lengthwise oscillation of the opposite end of the strap or bar. The bar 17 as shown in Fig. 1 is also bent or coiled

at the opposite end 20 so as to provide a cylindrical or tubular bearing or loop for supporting the roller 16.

Thus it will be seen that each roller 16 is supported by means of a pair of depending bars 17 detachably hooked over an end bar 11 or 12 of the cot or bed. The roller 16 is supported in the coiled or tubular ends 20 of the bars 17.

As hereinbefore stated the fabric shelf 15 is secured at its opposite ends to a roller 16. The ends of the fabric may be attached to the roller in any suitable manner and in the present instance this is accomplished by means of a metallic strip 21 adapted to be clamped at its opposite ends to the roller 16 by means of a pair of set screws 22. The end of the fabric shelf is first inserted between the strip 21 and the roller 16, and thereupon by tightening the set screws 22 the fabric will be securely clamped between the strip 21 and the metallic roller 16. The roller 16 is provided at opposite ends thereof with a series of threaded apertures or openings 23, and the bent end 20 of each supporting strap 17 is provided with an aperture or opening adapted to register with any one of the openings 23. By rotating the roller 16 within the bent or loop portions 20 any one of the threaded holes or openings 23 may be brought into registration with the hole or opening in the bent or loop portion 20, and by means of a set screw 25 screwed into a threaded opening 23 of the roller 16, the latter may be securely held in its adjusted position.

Thus, the fabric shelf 16 is suspended and held under tension between the rollers 16 at opposite ends of the bed, and in order to tighten the shelf or take up any slack, it is merely necessary to remove the set screws 25 from one of the rollers, grasp the roller between its ends and rotate it sufficiently to roll up and tighten the fabric shelf. Thereupon the set screws may be inserted so as to extend through the members 17 into a different set of openings 23 in the rollers. If desired the roller 16 may be provided with a squared opening 26 at one end thereof, and by means of a wrench having a squared portion adapted to be inserted in the opening 26, the roller 16 may be rotated for the purpose of tightening the fabric shelf.

As illustrated in the drawing the fabric shelf 15 is provided at one side edge thereof with a depending skirt 27, and secured to the outer side of the skirt are a series of pockets 28. These pockets may be formed from a single piece of material stitched to the depending skirt 27 along the sides and bottom thereof as shown at 29 and 30, three pockets being herein shown by way of example, or the pockets may be formed by folding up the skirt 27 and stitching at 29 and 30. The pockets 28 are readily adapted

to receive and hold various articles and may be closed by means of snap fasteners 31 and 32.

It will be noted that the pockets 28 depend or are suspended from the free side edge of the fabric shelf 15 and the pockets may be thrown up or folded over upon the shelf 15 at any time.

The fabric shelf 15 is thus stretched and suspended between a pair of opposite ends thereof only, and the side edges between the ends of the shelf are entirely free from any support. As a result the shelf is always easily accessible since the side edges will always extend in the same plane as the middle portion, so that after continued use in holding and supporting pillows and bedding, even though the fabric may give or sag, it will do so uniformly throughout its extent, whereas if the fabric were held between a rectangular frame instead of being suspended between its ends, the middle portion would sag considerably below the rigid framed edges, thereby rendering it difficult and almost impossible sometimes to reach in over the side bars, and grasp articles in the downwardly bulged middle portion of the shelf. Furthermore, this suspension shelf permits quick dismounting of the attachment and easy adjustment of the fabric to tighten or loosen the same. By means of the take-up devices or adjusting devices at the ends of the shelf, the proper degree of tautness or tension of the shelf may be obtained at all times.

Furthermore, by means of the detachable supports for the fabric shelf, the latter may not only be adjusted but readily removed and detached from one roller and rolled up entirely upon the other roller. Also the suspension shelf may be adjusted to accommodate various lengths of beds, and when the shelf supports are detached from the ends of the bed and the shelf rolled up upon one or both of the rollers, the entire attachment may be packed in a very small space.

Referring to Fig. 4 it will be seen that the depending bracket members 17 may be bent up at the lower ends thereof to provide upwardly extending portions 35 forming an open channel or loop within which the roller member 16 is freely seated. This construction permits quick detachment of the rollers from the supporting brackets for dismounting the attachment and also facilitates the assembling thereof.

It is to be understood that by describing in detail herein any particular form, structure, or arrangement, it is not intended to limit the invention beyond the terms of the several claims or the requirements of the prior art.

Having thus explained the nature of my said invention and described a way of constructing and using the same, although

without attempting to set forth all of the forms in which it may be made, or all of the modes of its use, I claim:

1. A shelf attachment for a cot or bed comprising two pairs of hangers, transverse members connected to the lower ends of said hangers, and a fabric shelf stretched between said members and beneath said bed bottom, said fabric shelf being unsupported 50
- 10 intermediate said members, and said hangers having at the upper ends thereof bent members adapted to embrace frame members of the bed, the bent members extending transversely to said transverse members.
- 15 2. A shelf attachment for a cot or bed comprising two pairs of depending hangers having means at the upper ends thereof for detachable connection to opposite ends of a bed, a transverse member supported by 55
- 20 each pair of hangers at the lower ends thereof, and a fabric shelf detachably connected at opposite ends to said members and suspended therebetween.
3. A shelf attachment for a cot or bed 60 comprising a pair of depending supporting members at each end of a bed, each of said members having at one end thereof a hook shaped portion adapted to embrace the end frame of the bed, a pair of transverse members including a roller member supported 65 at the opposite ends of said members, and a fabric shelf connected to and extending between said transverse members.
4. A shelf attachment for a cot or bed 70 comprising a pair of depending supporting members at each end of a bed, each of said members having a hook shaped portion adapted to embrace the end frame of the bed and also having a looped end portion, roller members extending into said looped portions and supported thereby, and a fabric shelf suspended between said roller members, said members being rotatably adjustable thereby to adjust the tension of said 75 fabric shelf.
- 45 5. A shelf attachment for a cot or bed comprising a pair of depending hangers at each end of the bed, each hanger at its upper end having a horizontally bent portion terminating in a downwardly and inwardly bent end adapted to embrace a frame member of the bed, transverse members connecting together the lower ends of each adjacent pair of hangers, and a fabric shelf suspended between said members. 80
6. A shelf attachment for a cot or bed comprising a pair of adjacent depending hangers at each end of the bed, a transverse member connecting together the lower ends of each adjacent pair of hangers, and a fabric shelf extending lengthwise between said members and suspended therefrom, each of said hangers having the upper end bent horizontally and downwardly to embrace a frame member of the bed, and the 85 horizontally bent portions of all the hangers extending in parallel relation lengthwise of the fabric shelf whereby the upper bent ends of the hangers will maintain the lower ends thereof against displacement by said shelf. 90
7. A shelf attachment for a cot or bed comprising a flexible shelf, depending hanger members adapted to be connected to a pair of ends of the bed, and transverse members connected to the lower ends of the 95 hanger members at opposite ends of the bed for suspending said shelf, one of said transverse members being rotatable to adjust said shelf.
8. A shelf attachment for a cot or bed comprising a fabric shelf, depending supporting brackets having means at the upper ends thereof for detachably connecting the brackets to opposite ends of the bed, and transverse members between which said shelf 85 is suspended, said brackets having means at the lower ends thereof for detachably supporting said members.

Signed at New York city, this 3d day of April, 1923.

CAROLINE M. TIMPSON.
